UNITED STATES PATENT OFFICE.

OTTO B. BLOCK, OF SHIPPENSBURG, PENNSYLVANIA, ASSIGNOR OF ONE-FOURTH TO
CHARLES E. HOKE, OF SHIPPENSBURG, PENNSYLVANIA.

FOLDING BED, DRESSER, AND WASHSTAND.

1,344,257.

Specification of Letters Patent. Patented June 22, 1920.

Application filed June 1, 1917. Serial No. 172,224.

To all whom it may concern:

Be it known that I, OTTO B. BLOCK, a citizen of the United States, residing at Shippensburg, in the county of Cumberland and State of Pennsylvania, have invented 5 certain new and useful Improvements in Folding Beds, Dressers, and Washstands, of which the following is a specification.

This invention relates to a combined 10 dresser, bed and washstand and has as its primary object to provide a compact article of furniture of the above character adapted to displace the use of separate articles of furniture for the purposes indicated.

15 The invention has a further object to provide a construction wherein the bed and washstand will be arranged within different compartments of the dresser so that one may be used independently of the other, the 20 device being also adapted to be used at the same time, as a dresser.

The invention has as a further object to 25 provide a construction wherein the bed will be normally inclosed within the dresser out of view and wherein the body of the dresser will be provided with a cupboard and also with a plurality of drawers which may be used for storing away the bed clothing.

30 A still further object of the invention is to provide a construction wherein the washstand will be arranged immediately beneath the top of the dresser and normally closed by slideable sections so that the washstand may be used by simply displacing the sections.

35 And the invention has as a still further object to provide the dresser with a water supply tank for the basin of the washstand and means whereby the said tank may be 40 filled without removing the dresser from its position against a wall.

45 Other and incidental objects will appear as the description proceeds and in the drawings wherein I have illustrated the preferred embodiment of the invention and wherein similar reference characters designate corresponding parts throughout the several views:

50 Figure 1 is a perspective view of my improved device showing the washstand opened,

Fig. 2 is a rear elevation showing the mounting of the supply tank for the basin of the washstand and the spout for filling the said tank. 55

Fig. 3 is a transverse sectional view illustrating the arrangement of the basin within the washstand and the position of the bed when folded within the body of the dresser.

Fig. 4 is a similar view showing the bed 60 extended,

Fig. 5 is a sectional view taken on the line 5—5 of Fig. 4 and illustrating the manner in which the drawer and the cupboard compartments of the dresser are swung out to 65 permit the extension of the bed.

Fig. 6 is a sectional view taken on the line 6—6 of Fig. 3 and illustrating the 70 mounting of the drawers in the upper corners of the dresser body.

Fig. 7 is a detail perspective view showing one of the swinging drawer compartments of the dresser body detached,

Fig. 8 is a fragmentary sectional view 75 showing the type of catch employed for holding the doors of the dresser closed, and

Fig. 9 is a detail perspective view illustrating the catch used to hold the bed in folded position within the dresser body.

In carrying out the invention I first construct the dresser which is formed with a hollow body having a bottom wall 10, end walls 11, a back wall 12 and a top wall 13. Arranged at the forward corners of the dresser body are vertical posts 14 and extending between said posts to abut the top wall 13 is a front board or wall 15. Supporting the dresser and secured to the bottom wall 10 of the body thereof are suitable legs 16. Upstanding from the rear edge of 80 the top wall 13 of the dresser body is a mirror frame 17 connected with the body of the dresser, as particularly shown in Fig. 2 of the drawings, by vertical cleats 18 arranged at the extremities of the frame. 85

Fitted within the mirror frame is a mirror 19. Fitted through the front board 15 at the extremities thereof, are dresser drawers 20. These drawers extend transversely into the dresser body at its upper portion and are, 90 as illustrated in Fig. 6, slidably received within drawer casings 21 secured within the

100

angles of the dresser body at its upper corners. Extending between the drawer casings 21 is the body 22 of a washstand. This washstand body is preferably formed of suitable enameled sheet metal and is connected in any approved manner either with the back wall 12 of the dresser body and front wall 15 or with the drawer casings 21. Formed in the top wall of the washstand body are suitable openings or depressions to removably receive water glasses or the like. Soap and comb trays 23 are also preferably pressed from the said top wall and a central opening is formed therein to removably receive a basin conventionally illustrated at 24. This basin may be of any approved character. As will now be observed upon reference to Fig. 1 of the drawings, the top wall 13 of the dresser body is provided with coacting slidable sections 25 having tongue and groove connections with the fixed portions of the said wall and shiftable outwardly away from each other to expose the washstand. This provides a construction whereby access may be easily had to the washstand and the sections 25 are, at their inner extremities, preferably provided with finger-receiving sockets 26 so that the said sections may be easily shifted. In the normal position of the sections 25, they close or house the washstand, as illustrated in Fig. 6, and complete the top wall of the dresser body for receiving various toilet articles. In this connection, it will be noted that such toilet articles may, when it is desired to open the washstand, be placed upon the sections to move therewith and thus render it unnecessary to remove the said toilet articles from the dresser.

40 Mounted upon the rear side of the mirror frame 17 is a water supply tank 27. This tank is preferably formed of suitable sheet metal and is relatively thin to occupy a minimum space in the rear of the dresser so that the dresser may be placed against a wall. The tank 27 seats at its extremities against the cleats 18 supporting the mirror frame and is secured to the said frame by suitable brackets 28. Leading from the bottom of the tank at a point substantially midway the ends thereof is a discharge pipe 29 which is carried through the back wall 12 of the dresser body into the washstand. As particularly shown in Figs. 1 and 3 of the drawings, the upper edge of the basin 24 is notched to receive the said pipe and the inner terminal of the pipe is equipped with a valve 30 of approved character for admitting water into the basin. In any instance where my improved dresser is to be employed in a house or other location where running water may be had, a supply pipe from the water system may be connected to the pipe 29 for supplying water to the basin 24 while the basin may also be provided

45 with a suitable discharge outlet for carrying off the water. Mounted upon the upper edge of the tank 27 is a filling spout 31 therefor. This spout at its inner extremity is provided with a laterally directed terminal 32 while the outer extremity of the spout is equipped with a funnel 33, the open side of which is partly closed by a top wall 34. Extending longitudinally from the inner extremity of the spout 31 is a lug 35 mating 75 with upstanding lugs 36 upon the upper edge of the tank 27 and pivotally connected thereto for swingingly supporting the tank. In advance of the lugs 36 the top wall of the tank is provided with a filling opening 37. 80 It will now be seen that the spout 31 may be swung inwardly upon the tank 27 to inactive position resting, as clearly shown in Fig. 2 of the drawings, upon the upper edge of the tank with the spout entirely hidden 85 behind the mirror frame. The funnel 33 of the spout is of a thickness substantially equal to that of the tank 27 so that when the tank is abutted against a wall, the spout will be free to move between the mirror frame 90 and the wall. Consequently, without disturbing the position of the dresser, the spout may be swung outwardly, as illustrated in Fig. 1, to active position. When thus swung outwardly the terminal 32 of the spout will 95 be shifted to fit within the filling opening 37 of the tank with the funnel disposed at one side of the mirror frame in such position that water may be readily poured into the funnel. I thus provide a construction 100 whereby the tank may, under ordinary circumstances, be easily filled while at the same time the filling spout for the tank will normally be concealed behind the dresser and in this connection attention is directed to 105 the fact that when the funnel 33 is shifted to lie against the upper edge of the tank, the top wall 34 of the funnel will prevent any drops of water remaining in the funnel from spilling out upon the floor. 110

115 The posts 14 of the dresser body are formed with pivoted sections 38 and 39 extending from the bottom edge of the front board 15 to the bottom wall 10 of the dresser body. These post sections are, as shown in detail in Fig. 7 of the drawings, provided at their extremities with trunnions 40 engaging with the upper fixed extremities of the posts and in the said bottom wall for rotatably supporting the said sections. Connected to the post sections 38 and 39 are mating door frames 41 and 42, respectively, adapted to fit within the open front side of the dresser body. The inner vertical rails of these door frames are provided with suitable knobs while the lower horizontal rails of the said frames are, at their outer extremities, equipped with spring catches of the type shown in detail in Fig. 8 of the drawings. These catches each preferably include a ball 130

43 loosely received within a suitable recess in the frame rail and held by a plate 44 connected to the lower edge of the said rail with the ball normally urged to project 5 through an opening in the plate by a spring 45. Arranged to coact with the ball is a socket plate 46 carried by the bottom wall 10 of the cabinet body. These spring catches will thus normally hold the door frames 10 closed while at the same time the said frames may be easily swung open. It will be noted that the movable sections or frames 41 and 42 are rigidly secured to the peripheries of the corner posts 38 and 39, a plane 15 lying midway between and parallel to the planes of the faces of each frame being directly radial to the axis of the adjacent post, whereby the posts will be exposed at the front of the dresser in all positions of the 20 movable frames with respect to said dresser.

Projecting laterally and inwardly from the door frame 41 is a drawer compartment 47 and slidably fitted within this compartment are a plurality of drawers 48 preferably of graduated depth and supported upon suitable cleats or guides 49 within the said compartment. Projecting laterally and inwardly from the door frame 42 is a cupboard compartment 50 similar to the compartment 47 and provided with a shelf 51. Normally closing the cupboard compartment 50 is a door 52 hingedly connected to the door frame 42 and equipped at its lower edge with one of the spring catches shown 35 in detail in Fig. 8, for holding the door closed. In the closed position of the door frames 41 and 42 the compartments 47 and 50 carried by the said door frames are, as shown in detail in Fig. 3 of the drawings, 40 received within the body of the dresser to terminate in spaced relation to the back wall 12 of the said body. At the same time, the door frames 41 and 42 may be swung outwardly upon the trunnions 40 for opening 45 the forward side of the dresser body.

Mounted within the dresser body is a bed which is formed of pivotally connected sections 53 and 54, respectively, hinged at the meeting longitudinal edges thereof. Each 50 section of the bed includes a preferably metallic frame in which is mounted one section of the bed spring and in this connection, it should be observed that any suitable type of spring may be employed. Swingingly connected to the innermost bed section is a head rail 55 while a similar foot rail 56 is swingingly connected to the outermost bed section, these rails being foldable inwardly upon the bed. Extending longitudinally of the inner bed section is a supporting rod 57. This rod receives the head rail 55 and projects at its extremities laterally with respect to the bed to engage within channeled tracks 58 countersunk into the 55 inner faces of the end walls 11 of the dresser

body. The tracks 58 extend from a point adjacent the lower inner corners of the dresser body and thence curve upwardly and forwardly toward the front edges of the said end walls. At their inner extremities 70 the tracks 58 are slightly offset to provide sockets 59 while at their outer extremities the said tracks are formed with similar sockets 60.

The bed is designed to receive a mattress 75 conventionally shown at 61 and normally the bed is folded within the body of the dresser, as illustrated in Fig. 3, behind the drawer and cupboard compartments 47 and 50. In the folded position of the bed, the 80 supporting rod 57 thereof is received within the sockets 59 at the lower inner ends of the tracks 58 with the bed sections folded upwardly to lie against each other, the mattress being tied or otherwise connected 85 to the bed to be carried thereby within the dresser. When the bed is thus disposed within the body of the dresser, it will be noted that the bed will be entirely concealed and connected to the bottom wall 90 10 of the dresser body is a spring catch 62, shown in detail in Fig. 9 of the drawings. This catch is arranged for engagement with the lower free extremity of the bed section 95 54 for holding the bed in folded position. For extending the bed, the door frames 41 and 42 are swung outwardly to the position shown in detail in Fig. 5 of the drawings. The catch 62 is then released when the supporting rod 57 for the inner end of the bed 100 is disengaged from within the sockets 59 of the tracks 58 and the bed pulled forwardly. The forward movement of the bed will cause the rod 57 to ride upwardly within the track 58 and engage within the sockets 105 60 at the outer ends of the tracks for rigidly supporting the bed at its inner extremity. Pivotally connected to the bed at the outer extremity thereof are foldable legs 63 which may be swung downwardly as 110 illustrated in Fig. 4 for supporting the bed in horizontal position. Clothing for the bed may be kept within the cupboard 50 as well as within the drawers 48 so that when the bed has been thus extended it may be 115 readily made up.

It will therefore be seen that I provide a particularly compact article of furniture comprising a dresser which may be used for all the ordinary purposes of a dresser, 120 a washstand which is readily accessible and a bed which will be normally concealed in folded position within the dresser body while at the same time the bed may be easily extended for use. The combined dresser, 125 washstand and bed will thus be adapted to displace the use of separate articles of furniture commonly employed for the respective purposes of the present invention while at the same time, an article of furniture is 130

produced which will be particularly desirable for use in any instance where living quarters are crowded.

Having thus described the invention, what is claimed as new is:

An article of manufacture comprising a body including upper and lower walls, corner posts interposed between the upper and lower walls of the body and each including 10 mating sections of different lengths, normally disposed in axial alinement and of the same cross sectional diameter, the upper post sections being permanently secured to the upper wall of the body and the lower 15 post sections being longer than the upper post sections and pivotally mounted for turning movement between said short post sections and the lower wall of the body, a front wall of the same width as and form-

ing a rigid connection between the inner 20 walls of the short post sections, and movable compartment sections each including a rigid front of less thickness than the adjacent movable post section and rigidly secured to the periphery thereof and movable 25 therewith, said compartment sections being adapted to fit between the front wall and lower wall of the body when in closed position, a plane lying midway between and parallel to the planes of the faces of each 30 rigid front being directly radial to the axis of the adjacent movable post section, whereby the entire posts will be exposed at the front of the body in all positions of the movable compartment sections with respect 35 to said body.

In testimony whereof I affix my signature,
OTTO B. BLOCK. [L. S.]
